CLAIM

The ornamental design for a kit assembly for adapting a gemstone between ring and pendant, as shown and described.

DESCRIPTION

FIG. 1 is an exploded perspective of a kit assembly for adapting a gemstone between ring and pendant;

FIG. 2 is a perspective view of the pendant base portion of FIG. 1, shown separately to show aspects of the design that are not visible when combined;

FIG. 3 is a front view of the pendant base of FIG. 2;

FIG. 4 is a rear view of the pendant base of FIG. 2;

FIG. 5 is a right side view of the pendant base of FIG. 2, the left side view being a mirror image thereof;

FIG. 6 is a bottom view of the pendant base of FIG. 2;

FIG. 7 is a top view of the pendant base of FIG. 2.

FIG. 8 is a perspective view of the ring shank portion of FIG. 1, shown separately to show aspects of the design that are not visible when combined;

FIG. 9 is a front view of the ring shank of FIG. 8;

FIG. 10 is a right side view of the ring shank of FIG. 8, the left side view being a mirror image thereof;

FIG. 11 is a top view of the ring shank of FIG. 8;

FIG. 12 is a bottom view of the ring shank of FIG. 8;

FIG. 13 is a perspective view of the head unit portion of FIG. 1, shown separately to show aspects of the design that are not visible when combined;

FIG. 14 is a right side view of the head unit of FIG. 13;

FIG. 15 is a front view of the head unit of FIG. 13;

FIG. 16 is a top view of the head unit of FIG. 13;

FIG. 17 is a bottom view of the head unit of FIG. 13;

FIG. 18 is a perspective view of the screw portion of FIG. 1, shown separately to show aspects of the design that are not visible when combined;

FIG. 19 is a side view of the screw portion of FIG. 18;

FIG. 20 is a top plan view of the screw portion of FIG. 18;

FIG. 21 is a bottom plan view of the screw portion of FIG. 18; and,

FIG. 22 is an exploded perspective view of the kit assembly for adapting a gemstone between ring and pendant of FIG. 1.

The broken lines in the drawings represent portions of the kit assembly for adapting a gemstone between ring and pendant and form no part of the claimed design.
